UNITED STATES PATENT OFFICE

HARRIS G. PARR, OF FORT WORTH, TEXAS, ASSIGNOR TO FORT WORTH WELL MACHINERY & SUPPLY COMPANY, OF FORT WORTH, TEXAS, A CORPORATION OF TEXAS

WELL-DRILLING-MACHINE DERRICK

Application filed April 1, 1927. Serial No. 180,268.

My invention relates to well machine derricks or masts and more particularly to means for pivotally connecting the derrick to the base structure of the machine and to bearings for the work end of the derrick; and the object is to prolong the life of derricks by preventing their deterioration by wear of the derricks at their points of connection with the supporting structure and for preventing deterioration of the parts of the derrick about the shafts at the work end of the derricks. Heretofore the derricks have been quickly worn out or destroyed by reason of the pivot bolts or shafts which were inserted 10 or run through the derricks near their ends. The object of this invention is to provide means for relieving the derricks of the direct strain caused by the pivotal connection of the shaft running through the derrick 20 members. Another object is to position the main sheave wheel substantially in the central part of the derrick members at the work end of the derrick and to avoid projecting parts on the sides of the derrick which might 25 be pulled or torn or broken off and dropped on the operators below. Other objects and advantages will be fully explained in the following description and the invention will be more particularly pointed out in the claims. 30 Reference is had to the accompanying drawings which form a part of this application.

Fig. 1 is a perspective view of a derrick and sufficient parts of a well machine to show 35 the application of the improvements.

Fig. 2 is a broken perspective view, showing how the derrick rests on the pivotal supports when the derrick is brought to inoperative position.

40 Fig. 3 is a detail view of a bearing.

Fig. 4 is a side elevation of the upper end of the derrick.

Fig. 5 is a rear elevation of the same.

Fig. 6 is a perspective view of one of the 45 work end bearings.

Fig. 7 is a detail sectional view, taken substantially on the line 7-7 of Fig. 4.

Fig. 8 is a vertical section of one of the bearings at the upper end of the derrick.

50 Fig. 9 is a perspective view of one of the

bearings in the upper or work end of the derrick.

Fig. 10 is a plan view of the work end of the derrick.

Fig. 11 is a face view of one of the bearings 55 for the sand line sheave wheel shaft.

Fig. 12 is a side elevation of the same, showing the oil reservoir in dotted outline.

Fig. 13 is a detail view of the shaft for the casing line sheave wheel, showing the 60 manner of lubricating the sheave wheel.

Similar characters of reference are used to indicate the same parts throughout the several views.

The drawings show parts of a wheeled well 65 drilling machine, the wheels being omitted. The drawings show an axle 1, longitudinal sills 2 and a cross-beam 3 to which the axle 1 is attached. The machine is provided with derrick supports or posts 4. The derrick 70 herein shown is not connected directly to the supports 4. Bearing members 5 are attached throughout their lengths to the derrick members 6 and made securely rigid therewith and the bearing members 5 are countersunk 75 in the derrick braces 6' and attached thereto by suitable bolts which run through the braces 6' and the bearing members and through the derrick members 6. The derrick members 6 are not engaged by the pivot 80 shaft 7 as heretofore. Bearings 8 for the pivot shaft 7 are attached to the bearing members 5 and engage and turn on the shaft 7. This structure makes the pivotal connection of the derrick with the well machine 85 and the braces 6' and bearing members 5 strengthen the derrick and make the derrick secure against creening or lateral motion. The derrick supports 4 are made rigid with the machine frame by bracing members including a cross-bar 9 which is attached to the supports and by the braces 10 which are attached to the cross-bar 9 and to the longitudinal sills 2, the supports 4 being attached 90 to the sills 2 by bolts 11. In order to prevent spreading of the supports 4 in the operation of the machine, bearings 13 are provided for the ends of the shaft 7 and attached to the supports 4 and bolts 12 are run through the 95 bearings 13, through the shaft 7, and through 100

the supports 4. The derrick can be swung freely on the shaft by reason of the bearings 8 which turn on the shaft 7. There is an advantage in tying the supports 4 against spreading by the means shown because there are no parts of the shaft or bearings projecting laterally beyond the supports 4 which would interfere with the walking or spudding beams (not shown). The derrick members 6 are generally made of wood and are of great length. The advantage of this invention is that the derrick members are made rigid and are not weakened by making holes through them and the strain is distributed by the bearing members 5 and the braces 6'. The bearing members 5 are not weakened by holes through them as the bearings 8 engage the pivot shaft 7 and are attached to the bearing members 5. The derrick members 6 are not made weak by wear because the bearings 8 on the bearing members 5 prevent any wear of the derrick members. For making the meaning of the derrick clear, the pivoted end of the derrick will be hereinafter referred to as the base of the derrick. The lower end of the derrick is strengthened by a cross-brace 14 attached thereto.

The work end or top of the derrick is improved and strengthened. Longitudinally extending bearing bars 15 are attached to the sides of the derrick members 6 for accomplishing three functions. They strengthen the upper ends of the derrick members, make separate bearings supports to take strain and wear off the upper ends of the derrick members, and provide means for preventing the drilling cable from "jumping" or being thrown from the sheave wheel 16. The upper ends of the derrick members 6 are cut away for insertion of the bearings 17. The bearings 17 and 18 are thus countersunk in the derrick members 6 and also in the bearing bars 15. The bars 15 extend below the cut-away portions of the derrick members 6 and are attached thereto by suitable bolts. It will be understood that both derrick members 6 are provided with such bearing equipment. The bearings 17 and 18 have angular webs or flanges 20 by which the bearings are attached together with suitable bolts, which bolts extend down through bracing bars 15 and the vertical portions of the flanges on member 17 bear against the outsides of the bars 15. The member 17 of the bearings has a stud or lug 19 which projects down into the derrick member 6, as shown in Fig. 7. In this manner the bearings 17 and 18 are fixed against movement on the bars 15. The bearings 18 are provided with oil reservoirs 21 and the reservoirs 21 have openings 22 by which the lubricant or oil is supplied to the reservoirs. The lubricant escapes from the reservoirs 21 to the shaft through apertures 23. One advantage of the construction of the reservoirs 21 is that the reservoirs are

formed in a single piece, the cap being formed integral therewith. There is nothing to be displaced as where the caps are made in separate pieces and secured to the reservoirs. The bearings and their connections take the direct strain from the derrick members 6 and there can be no wear of the derrick members. The outer ends of the shaft of wheel 16 are flush with the outside of the bearings 17 and 18. The derrick is provided with means for preventing the spreading of the members of the derrick. A block 33 is mounted between the derrick members 6 and metal bars 34 are mounted on the outsides of the members 6 and the bars 34 are secured by bolts and nuts which project through the bars 34 and the derrick members 6 and the block 33.

For similar reasons just stated above, improved bearings are provided for the shaft of the sand line wheel 24. Bearings 25 are attached to the derrick members 6, being partly countersunk therein and provided with flanges 26 for attaching the bearings to the derrick. The bearings 25 are provided with lubricant reservoirs 27, indicated by the dotted outline in Fig. 12, and provided with inlet opening 28. The construction and arrangement of the bearings 22 are such that the ends of the shaft of the wheel 24 are substantially flush with the sides of the derrick members 6.

The derrick carries a sheave wheel 29 of the casing line pulley. Improved means are provided for oil or lubricating material for the shaft of wheel 29. Fig. 13 illustrates the lubricating means. The shaft 30 is provided with a duct 31 which leads from a filling nozzle 32 and the duct extends substantially to the central parts of the wheel 29 for supplying lubrication to the wheel.

What I claim, is:—

1. In a well drilling machine provided with a derrick; means for preventing the spreading of the base end of said derrick consisting of a non-rotatable shaft, bearings attached to said derrick and engaging said shaft, bearing supports for said shaft, bearings attached to said supports and engaging said shaft, and bolts projected through said supports and the bearings attached thereto and through said shaft, a sheave wheel for a drilling cable, a pair of bearings and a shaft for said wheel journaled in said bearings, each bearing having a depending lug bearing against the outside of the derrick for preventing the spreading of the parts of the derrick and each bearing being partly embedded in said derrick.

2. In a well drilling machine provided with a derrick pivotally connected thereto; a sheave wheel for the work end of said derrick, bearing bars attached to the sides of said derrick at the work end, and means for mounting and centering said wheel in the work end of said derrick consisting of a shaft

and bearings for the ends of said shaft journaled in said bearing bars, said bearings being partly embedded in said derrick and partly embedded in said bearing bars, and lugs depending from said bearings bearing against the outside of said derrick, and each bearing being provided with a lubricating reservoir for lubricating said shaft, and each reservoir being provided with a cap.

5 10 3. In a well drilling machine provided with a derrick in two parts pivotally connected to said well drilling machine; sheave wheels for the work end of said derrick and shafts therefor, bearings for said shafts embedded in said derrick, and means for lubricating said shafts, the ends of said shafts and said bearings being substantially flush with the outsides of said derrick.

15 20 4. In a well drilling machine provided with a derrick in two parts pivotally connected thereto; sheave wheels for the work end of said derrick and shafts therefor, bearings for said shafts embedded in said derrick, means for lubricating said shafts, the ends of said shafts and the bearings therefor being approximately flush with the outsides of said derrick, and reservoirs for the bearings of the cable line sheave wheel provided with caps integral therewith.

25 30 In testimony, I set my hand, this 24th day of December, 1928.

HARRIS GREGORY PARR.
